UNITED STATES PATENT OFFICE.

JAMES K. DARBY, OF DAYTON, OHIO, ASSIGNOR TO FRANK C. TROWBRIDGE, OF HAMILTON, OHIO.

PAPER-MAKING MACHINE.

Application filed January 30, 1926. Serial No. 84,845.

This invention relates broadly to paper making machinery.

More specifically, this invention relates to improvements in paper making machines of the Fourdrinier type.

One of the objects of this invention is to provide a paper making machine which is simple in construction, efficient in operation, and economical in manufacturing, and maintenance.

Another object of the invention is to apply both the telescopic principles of my Patent No. 1,436,240, patented November 21, 1922, and those of the machine of the Marshall type, shown in Patent No. 507,744, patented October 31, 1893, in which the machine has all the wire carrying parts on a transversely movable truck. My idea is to apply these features to a machine having a sealed top couch housing.

A further object of this invention is to apply the principle of telescopic wire stringing machines without removing any rolls from the frame within the wire loop, and to pass the entire machine, table and bottom couch roll through the wire loop at one time.

A still further object of the invention is to provide a machine in which all the rolls within the wire loop are withdrawn, requiring but one operation in forming a slack loop from the couch to the breast housing.

A still further object of the invention is to apply a downhill auxiliary lift system to aid in the transverse movement, both forward and return of all the machine elements within the wire loop.

Another object is to provide a cable system to aid in stringing the Fourdrinier wire, in order that the wire may be replaced on machines of great width and length without injury to its meshes.

A still further object of this invention is the special arrangement of the breast housing, deckles, forebay, head box, slices, and lock bolts, so that after their removal for the purpose of placing a new wire on the machine, they may be replaced back to their original position within a thousandth fraction of an inch.

Another object of the invention is to raise and lower the breast end of the machine on and off the auxiliary wire stringing lifts by means of the normal breast roll vertical adjustment.

Another object of this invention is to provide a self-contained water supply system and suction manifold, a compound self-contained shake, a curved plane forming table vertically adjustable, and a double roll suction box system in combination with a high speed rotary vacuum pump.

Further objects of my invention will appear from time to time in the specification.

This invention consists substantially in the construction, combination, location, and relative arrangement of parts, all as will be more fully hereinafter set forth, as shown by the accompanying drawings, and finally pointed out in the appended claims.

Referring to the drawings, in which the same reference numeral refers to the same part wherever it occurs through the several views,

Figs. 1, 1^A and 1^B, taken together, represent a side elevational view of the front end of my improved paper machine in normal position, ready to operate.

Figs. 2, 2^A and 2^B, taken together, represent a front side elevational view of my improved machine, ready to receive a new wire.

Fig. 3 is an end elevational view, partly in section, with some parts broken away, of the couch end of my improved machine.

Fig. 4 is a side view of the suction boxes used in my improved machine.

Fig. 5 is an enlarged, detailed view of the breast roll.

Fig. 6 is a top plan view of the detail of Fig. 5.

Fig. 7 is an enlarged, detailed view of the breast housing showing the flexible link connections to the forming table.

Figs. 8, 8^A and 8^B, taken together, represent a rear elevational view of my device in position, ready to receive a new wire.

Fig. 9 is an end view, partly in section, with some parts broken away, showing both the suction boxes and exhaust manifold.

Figs. 10, 10^A and 10^B, taken together, represent a top plan view, showing the parts of the machine within the wire loop, moved transversely of the main portion of the machine.

Fig. 11 is an end elevational view of the machine showing the interchangeable couch rolls.

Figs. 12 and 12^A, taken together, represent a more or less diagrammatic view of the

machine of my invention, showing the cable means used to support the new wire loop as it is being placed in position.

Fig. 13 is an end elevational view of the 5 breast roll moved transversely from within the wire loop.

Fig. 14 is a top plan view of the deckles, slices, forebay and head box.

Fig. 15 is an end view of the breast housing.

Fig. 16 is an end elevational view of the wire truck used to support a new Fourdrinier wire in readiness to be put in place on the machine.

Fig. 17 is a side elevational view of this wire truck.

It has always been an inherent difficulty in connection with the operation of Fourdrinier paper making machines, that great care and skill are required in the operation of placing a new Fourdrinier wire on the machine. As is well-known, these Fourdrinier wires are made up in the form of a fine mesh, constructed of fine copper or brass 20 wires, and are therefore easily kinked, causing the wire either to break when being placed in the machine or after it has been run a short time. In large machines, these wires often attain a width of 200 to 300 25 inches. It is therefore apparent that these wires must be handled with great care, in order to prevent injury thereto.

Three methods have been used in restraining the Fourdrinier paper machine. The 30 first method consisted in feeding the wire over the rolls, then along the tables, and finally joining the two free ends together, forming a closed loop. This took great skill and a relatively long time to complete, and 35 injuries to the wire often resulted. In the Marshall type of machine, parts of the machine were moved transversely, and the wire loop strung on them. However, this required that many of the parts be removed 40 from the main body of the machine before the transversely movable parts could be withdrawn. This was a great disadvantage, and the machine never came into practical use. The Darby machine disclosed in the 45 above mentioned patent, used the telescopic principle, in which the half of the machine including the lower couch roll was moved longitudinally of the whole machine, in order to shorten it, and the wire was then 50 more easily strung in place. In this invention, these two fundamental principles are utilized in a greatly improved manner. All the parts within the wire loop are moved transversely of the main portion of the machine, with the removal of but a few parts, and at the couch end of the machine, the 55 lower couch roll is moved longitudinally toward the main body of the machine, as will appear more fully hereinafter. My invention also contemplates a new lift device, a

new construction of the side arms, a new breast roll arrangement, a novel down-hill transverse transportation system for the parts within the wire loop, and a new and novel wire carrying truck.

Referring to Figs. 1, 1^a, and 1^b, which, taken together, form a front side elevation of the machine, 1 is a top couch roll journaled at 2 in split bearing 3, which is secured at 4 to the swinging arm 5. Attached 70 to the upper side of the swinging arm by bolts 7 is an angle plate 6, having bolted thereon by means of bolts 9 the guard board 8. The swinging arm 5 is mounted in a bearing on the upper end of the upright 11 80 by means of short pins 10. As is of course evident, this structure is exactly the same on the back side of the machine. The upright 11 is bolted to the foundation at 17. Also bolted to the foundation at 18 are supporting blocks 19, which, in turn, support blocks 21 secured to the blocks 19 by means of bolts 20, and centered thereon by means of keys 22. Keyed by means of keys 24 and secured by means of bolts 23 to the top portions of 90 blocks 21 are split bearings 25, in which is journaled the shaft 31, which supports the lower couch roll 30. The dotted lines 41 indicate a track which is on the same level with the top edge of block 21, extending inside of 95 the uprights 11, and also on a level with the top edge of removable blocks 42, forming a track along which the bottom couch roll 30 can be moved, as will be more fully described hereinafter. The blocks 42 are also secured 100 to the upright 11, by means of bolts 43, and are in turn, secured to the foundation by means of bolts 44.

Extending vertically thereof, and at one end of the blocks 42 are heavy metal sections 105 45, having mounted therein swivel pins 46, passing therethrough and securing thereon saddle bearings 50. Small dowel pins 47 lock the swivel pins 46 in place by passing through the hole 47^a in bolt 46 (Fig. 8).

The saddle bearings 50 have mounted therein short pins 51, which are secured in place by means of lock nuts 52. These pins extend through the side foundation rails 60, which secure them to the saddle bearings.

It will be understood that the swivel pins 46, and the saddle bearings 50, in combination, form universal supporting joints for the side foundation rails 60.

At 61 is a drop extension section of the 120 foundation rails 60, the upper edge of which is on a level with the track 41, and the top of block 42, and forming a continuation of the track. The end of this extension is curved at 62 and abuts against the block 42 125 for a purpose which will be described later.

At 71 is a main water supply pipe, consisting of a coupling 72, a short removable section 73, another coupling 74 and a short section 75 which is secured to the distribut- 130

ing pipe 76 which extends along the side of the machine, and is supported on the side foundation rails 60 by suitable means as clamp 76^a (Figure 9).

5 In the drawings, for convenience, this supply pipe 71 is shown at a distance from the saddle bearing 50, whereas in practice, it can be mounted directly in front of the saddle bearing so as to be movable about 70 that point as a center. Shower pipes 77 tap into the distributing line 76 wherever desired, and a supply pipe 78 runs to the back side of the machine, as is clearly shown.

10 A tap for suction box use is shown at 79. 15 It will be noted that the water supply system is self-contained and mounted on the machine frame, and conveniently arranged for operation and inspection from the front side of the machine.

20 At 81 is a guide roll for which no bearings have been shown for the sake of clearness, since their inclusion would only serve to confuse the drawing, and they are furthermore well known and understood in the 25 art.

25 Mounted under the machine are the carrying rolls 84, over which the lower portion of the wire loop moves. These rolls also have a special purpose in stringing a new 30 wire, as will be described later.

35 Bolted to the side foundation rails 60, at 86, is a cross brace 87, in turn bolted at 88 to the suction table rail 91, and thus by these means permanently tying together the front and back portions of the machine.

40 The rails 91 are shown with an offset portion 92 bolted at 93 to the rails 60, thus forming an open section which serves as a support for the suction boxes to be described later.

45 At 94 are shown the table rolls which are to be supported on saddle bearings not shown for the sake of clearness.

50 Rigidly secured to the rails 91 are sockets 95 which serve as supports for dandy stand posts 96, and a dandy roll 99.

55 Rigidly secured to the rails 60 at 100, are sockets 101 which pass through rails 91 and serve as receptacles for the vertical stands 102, upon the upper end of which are the split bearings 103, which support short transverse jack shafts 104 and deckle pulleys 105. The usual construction is to pass the shaft 104 entirely across the machine, but in the present construction, short jack shafts 104 are used for a reason which will appear hereinafter. Also bolted to rail 60 at 110 are special stands 111, bolted on their upper ends at 112 to rails 91.

60 It has been the usual practice in connection with suction boxes, to employ as high a vacuum as possible, and to close off all points of leakage. When such high vacuums are used, they tend to increase the friction between the wire and the top of the suction

boxes, causing the wires and boxes to wear out rapidly. A high vacuum also tends to draw the paper pulp through the wire, causing holes in the finished product. I have found in actual practice that a partial vacuum of 5" is the most desirable for two reasons: Firstly, a one-sixth partial vacuum does not place such a heavy duty on the suction pump, and this prevents it from slipping and causing the paper to break; and 75 secondly, with lower vacuums only the water of flotation is removed. If a very high vacuum is utilized, there is a tendency to remove the water combined with the pulp which causes the paper to be of different colors on 80 its two sides. This has been blamed to poor coloring materials, whereas it is my opinion that the paper acts as a thin membrane, and the high vacuum causes the phenomenon of dialysis. In this action, the soluble acids 85 are caused to pass through the paper pulp to the bottom, leaving the paper basic on its upper surface and acid on its lower surface. Also some of the valuable acids may be removed by the suction pumps, resulting in a low quality paper. It is therefore my purpose, by means of my low vacuum suction boxes, to prevent the removal of these acids, and thus prevent the production 90 of paper lacking in valuable physical properties. 95

100 Referring now to Figs. 4 and 9, in which is shown the structure of my improved vacuum boxes, 119 represents transversely extending rails secured by bolts 117 within the offset portion 92, of rails 91 which serve to support the suction roll boxes 118 of the table roll type. Mounted on the suction boxes are the vacuum boxes 120 having wide flanged edges 120^a and a central longitudinally extending partition 120^b. On the top of the vacuum box is a hollow suction head seal 121, having grooved edges 121', which are clamped onto the edges 120^a. At that section of 121 where the hollow section is directly over the edge of the wire, the box is cut away as shown in Fig. 9. The resulting raised portion would admit air to the vacuum box 120 at the edge of the wire. Therefore I provide a soft woolen sack member 122, extending over the edge of the suction head seal 120, and securely clamped thereto by means of the member 123. By means of the holes 122^a, priming water is passed to the sack 122, causing the wet felt to 115 seal off the edges of the wire on the outside of the deckles. A water connection 124 supplies a continuous flow of priming water to the felts 122, thus causing the wet felt on the outside of the deckle edge to prevent any 120 leakage along the edge of the wire.

125 A table roll 125, is mounted on adjustable bearings 125^a to allow for an adjustment of the roll with respect to the suction head seal.

130 In Fig. 4 are shown the doctor plates 126

which clean the surface of the table rolls 125 by removing any fibre, grease or gum which may stick thereto. These doctor blades 126 are supported on stands 126^a.

5 A drain pipe 127 connects at 127^a to a flange member 128 on the suction manifold 130 which is supported on the side foundation rail 60. Another flanged member 132 mounted on the side of the suction manifold 10 is connected to a short curved pipe 133, which leads to the suction pump 136. Clamps 129, 134^a are used to hold the short sections 127^a and 133 in operative position. In the upper end of the pipe 127 is a plug 15 valve 135, which may be operated from one side of the machine by means of a key 135^a. The suction pump 136 may be of the high speed rotary cycloidal type.

The object of this combination of a table 20 roll suction box and a high speed rotary cycloidal suction pump is to provide a system that has a high suction impulse, and therefore one which produces a steady suction, not only on the filter water which enters the vacuum box, but also on the air which must be drawn off to maintain a steady vacuum.

In building suction boxes, it has always 30 been the practice to cut down as much as possible the friction area, but this causes the boxes to operate defectively as the air is carried into them on the bottom side of the wire. Therefore it will be noted that I have provided flanged edges 120^a on box 120 35 which are unusually wide, so that as the wire side passes over these edges, but little friction is formed as a thin coat of water clings to the bottom side of the wire, tending to prevent friction.

40 Elevation screws 116 are shown to properly level the boxes 118.

Referring again to Figs. 1, 1^a and 1^b, the special stand 111 is constructed to receive a pivot pin 140, which locks table rails 141 of 45 the breast end in a flexible manner to rails 60 and 91 of the couch end. Rails 141 are not secured to rail 60 by bolts, but are arranged to be adjustable in segments. At 50 142 is shown a jointed rail 141 clamped together by bolts 143 to a cross I-beam 144 which in turn rests lightly on rail 60, but is not bolted thereto, for reasons which will be described later.

At 150 is a hanging stand 151 dependent 55 from table rails 141 in which is journaled supporting roll 152 which is intended to be within the wire loop. Roll 153 is supported in a similar manner, and is intended to be outside of the wire loop. Near the breast 60 end of the machine, another roll 152 is similarly supported within the wire loop.

Bolted to rails 60 at 156 are socket stands 157, supporting a vertical post 158, having a transverse arm 159 extending between 65 them beneath which a trough 160 is sup-

ported. This assembly forms a removable deckle return support. A split bearing housing 175 bolted to the foundation plates, supports an adjustable breast housing base on pins 178; and bored support 179 permits an elevation screw 180 free movement therein. A ball joint cap 181 is provided on the top of screw 180. A member 182 secured to the side of support 179 supports a stand 184, on which is mounted a worm 185 70 75 enmeshed with gear 186 mounted on the screw 180. Supported on the ball joint socket 181 is an adjustable breast section 195 having a projecting shelf under rail 60, provided with a ratchet jack 196.

Resting loosely on section 195 is another section 199 hollowed at 200, and in which is mounted a lock pin 201 and secured in place by means of lock nut 202. A safety taper pin 204 locks an extension link 205 in the projection 207 of section 199, which extends to a like lock pin 206 secured in place by means of lock nut 208 and safety pin 209. By this arrangement, the short link 205 is pivotally secured to the member 199, and the foundation rail 60. It will, of course, be evident that an exactly similar construction will be found on the back side of the machine. By this means, side foundation rails 60 are 90 95 locked securely to breast section 199. Section 179 and section 195 do not shake, but support 199 does slide to and fro with a shake motion. Also the breast housing parts 179, 195 and 199 can swing on an arc centered at 178, so that the entire assembly forms 100 a self-contained structure which swings into and out of operative position.

A curved arm 222, bolted at 223 to the section 199 forms a ball and socket joint at 224 and 225. The member 225 supports a hollow tube 226 extending across to the back side of the machine and supporting the deckle frame 240 at this point. A breast board 227 bolted at 228 to a cross brace 221 has a brass plate 229 mounted thereon, and extending across the machine in close proximity to the breast roll. Bolts 230 and 231 secure brackets 232 to the breast board 227, and breast section 199 at the cross brace 221.

Bolts 235 secure a small stand 236 to the 115 top rail 60 on the outside of rails 141 and form with the member 238 a ball and socket joint. The member 238 supports a hollow tube 239 extending transversely across the machine and serving to support the member 240. This completes the deckle frame support. It will be noted that the breast housing and the deckle frame supports and assembly are independent of the table rails 141. A stand 245 supports a deckle wash 120 trough 246 from which depends a drain pipe 125. The trough 246 is also supported on the deckle frame by means of angle iron 248, secured to the offset portion 249 of the deckle frame. This portion 249 forms a deep box 130

like forebay over the breast housing. A deckle return segment wheel 250 is formed into a grooved passage by means of plates 251 extending from the trough to the lower section 5 of the deckle frame. Spaced at several points around the periphery of the section 250 are small wheels 252 which serve to eliminate any friction as the deckle straps 400 travel over them. A high pressure gate 10 regulates the flow of stock by means of the weight 253 pivoted at 254, automatically adjusting the gate 255, shown by the dotted line.

The slices 256 extend from near the breast 15 plate 227 and wire W to a point above the top return of the deckle strap 400, as is clearly shown in Fig. 1^b. Clamps 260 secure the forebay 249 to the head box 265 and to the breast board 227. It will be noted by this 20 arrangement that the wash trough 246, segment wheel 250, and the side walls of the forebay 249 have been coupled together in such a manner that they occupy a relatively small longitudinal space and are therefore 25 more directly above the breast housing support.

The breast roll 280 is journaled at 281 in split bearings 282, which are mounted on the bearing support 290 secured to table rails 30 141 by bolts 291. The bearing block 290 has a drop flange section 293 for a purpose which will appear hereinafter.

A self-adjusting breast roll wipe board arrangement is shown in the member 300, 35 bolted to the rail 60 by means of bolt 301. A slot 302 is provided in the outer end of the member 300, in order that its position may be adjusted with respect to the roll 280. (See Fig. 6.) Mounted on the other end of 40 the arms 300 is a breast wipe board 306 supported by a tapered bar 305.

It will be noted that in the machine of the Marshall type the equivalent of member 300 must be removed before a new wire can be 45 strung, but in this device this is unnecessary.

Securely fastened to the side foundation rails 60 in both the front and back sides of the machine are three assemblies 390'. At the 50 breast end, immediately beneath the truck assembly 390' is a stand 377 permanently bolted to the foundation. A similar structure is shown at the central section of the machine, while at the couch end, the truck 55 wheels 390 are secured to the drop section 61 and beneath them on the block 42 is the jack 360. The exact purpose of these truck structures and the jack 360 will appear more fully hereinafter. The above completes the 60 description of the present machine from the front side in normal operative position.

The normal condition of the machine in condition to operate and produce paper has been shown in Figs. 1, 1^a and 1^b. I will now 65 describe the necessary steps to place the ma-

chine in condition for a renewal of the Fourdrinier wire.

To remove the old wire W it is cut across the face of the bottom couch roll 30 and the power turned on, causing the top and bottom couch rolls to feed the wire through the nip where it is rolled into a spool and removed entirely from the machine.

The machine is now ready for a new wire 75 which is placed on in the following manner:—The top couch roll and assembly are raised up out of operative position by swinging the arms 5 upwardly about their pivots as shown in Figs. 2, 2^a and 2^b. The jaw clutch 32 (shown clearly in Fig. 3) is disengaged from the power source and the couch bearing 25 is unbolted and the key 24 is removed from the slot 24'. The roll 30 and its bearing 25 are now free to move along on the block slideway 21, 41 and 42, 80 over on to the drop section 61 of the side foundation rolls 60, as shown at Figs. 2, 2^a and 2^b. This is accomplished by the crank 29^a, which rolls up cable 28 suitably attached 85 to the bearings 25. 90

Referring to Fig. 3, it will be noted that the top couch housing at the lower section 12 has been offset in such a manner as to permit the bottom couch roll 30, journal 31, clutch 32 and bearing 25 to pass back 95 through the housing section 12. Section 11' of the top couch housing, therefore, forms an overhanging structure, while the usual extended journal 31 has been cut off even with the bearing 25, so that no extension lift 100 can be applied to raise the bottom couch roll 30, as has been the custom. Also jaw clutch journal 31 on the back side has been formed into a unitary structure comprising 105 an end spider, journal and jaw clutch. 110

The main water supply is shut off by suitable valve (not shown), and disconnected at 71 and 75. The dandy roll 99 is removed from its bearing on post 96; the carrying rolls 84 on the outside of the wire loop are 110 taken from their bearings and laid on the foundation, as shown at 84. In this position, these rolls serve as points of rest for the slack wire loop while being replaced, so as to prevent it from dropping into the pit 115 or buckling. As the transverse movable part of the machine passes into the wire loop from the back side of the machine, the deckle pulley 105, dandy stand 96 and deckle trough 160 remain on the rails 91 and 141 but may be turned in their socket supports so as to be out of the way. Likewise, the front deckle 400 is removed and laid on the floor 120 as shown in Fig. 12^a. Roll 153 supported on rail 141 is removed and laid upon the foundation plates at 153 but as there are not sufficient rolls 84 and 153 on the outside of the wire loop to properly guide the slack wire, I provide two additional members 152 to provide 125 a sufficient number of points of support, 130

to thereby prevent buckling and kinking of the wire.

The dowel pin 47 in Fig. 1 is withdrawn, permitting the swivel pin 46 to be lowered 5 to release the saddle bearing 50. It is to be noted that the curved end 62 on the offset portion 61, of the foundation rails 60 abuts lightly against the block 42. This serves as a positive means of aligning the side foundation rails with the top couch housing. The jack 360, securely bolted to block 42 directly beneath truck wheels 390 supports a transverse beam 370, which serves as a track for the truck wheels 390.

15 As has already been indicated, Figs. 2, 2^a and 2^b, and Figs. 8, 8^a and 8^b, are side elevational views of the front and back sides, respectively of my improved machine.

It will be noted that the general construction of this machine on the front and back sides is exactly the same, the only changes between them being those necessary to adapt the parts of the machine within the wire loop to transverse movement. Therefore, to repeat in detail the construction of the back side of the machine will be unnecessary.

Referring to the back side in Figs. 8, 8^a and 8^b, the grooved plate 63 has been bolted to the block 42, causing the member 61 on the back side of the machine to be shorter than the corresponding member 61 on the front side, so that as the parts within the wire loop are moved transversely, the back side framework being shorter than that of the front side, passes readily between the supports without meeting with any obstructions. This construction will also be found at the breast end of the machine. There are, of course, other ways of accomplishing 40 this result as, for instance, the ends of the machine could be placed on a diagonal with respect to the longitudinal axis of the machine to accomplish the same result.

The jaw clutch 32 is not shown in this figure for the sake of clearness, since it is clearly disclosed in the end views.

The truck wheels 390, the rails 370 and jacks 360 are provided on the back side of the machine in a manner similar to those on the front side.

As before, dowel pin 47, locking swivel pin 46 at 47^a, is withdrawn from the saddle bearing 50, and at 77 is shown the end of the shower pipe which extends transversely 55 across the machine from the front side.

The suction boxes 118 are shown with the discharge pipe 127 connected at 128 to a manifold 130, which is divided into two sections joined together by a valve 129'. At 60 133 is a suction pump manifold leading to the main suction pipe 134 of the suction pump (not shown). It has been the usual custom to bolt the manifold 130 to the floor at the rear of the machine, and then to un- 65 couple each suction box individually, but

in my construction, the manifold 130 has been bolted to the side foundation rail 60, and therefore by releasing the coupling between 132 and 134, the machine is free to move out transversely without in any way disturbing the suction boxes or manifold.

The suction pump connection 132, 134, is shown at one side of the saddle bearing 50 but in actual construction, it is connected with it and lies directly in front of the center bearing 50, about which line it moves as a center, whenever the forming table is to be adjusted vertically. The dandy stand 96 is taken from the socket 95 and laid on the floor.

80 The deckle pulley 105 and vertical post 102 are removed from their socket bearing 101 and placed on stand 107, bolted to the foundation plates, and therefore do not move transversely with the rest of the machine. The front deckle strap remains hanging on the pulley as shown.

85 The back side deckle support 158, 159 and 160 is removed from the socket bearing 157 and rests on the stand 191 which is bolted to the foundation plates.

90 The self adjusting breast wipe board arrangement 300, being supported by the breast roll journal 281 and side foundation rail 60, is within the wire loop and need not be removed.

95 At 350, the short stroke shake beam is detached by removing the wrist pin (not shown).

100 Referring to the side elevation, Figs. 2, 2^a and 2^b, and 8, 8^a and 8^b, it will be noted that the breast housing supporting the side foundation rails at the breast end is capable of being withdrawn from normal position and swung back clear of the parts to be 105 moved transversely about the shaft 178.

110 Since a machine using 110 feet of wire of from 200 to 300 inches wide would have a weight of the order of 100 tons if it were moved by means of power, special provision would have to be made to provide such power movement, but in my present invention, transverse movement of the parts within the wire loop is secured by utilizing the force of gravity.

115 In Fig. 3 is an end view of Figs. 2 and 8, showing the forming table at the couch end, ready to move out transversely. The transverse rails 370 provide tracks for the truck assemblies 390' bolted at intervals to the bottom side of the foundation rails. The truck assemblies are provided with small wheels 391, as well as the larger wheels 390. By this construction a double truck is formed which better distributes the load upon the rails, as well as preventing any twisting strains upon them, and thus tending to hold them in alignment. The lower end of the bottom couch roll bearing 25 has drop flanges 26 forming a slideway on both sides 120

125 130

of section 60, which helps to cross brace the machine on its trucks. These drop flanges may extend downward as far as desired. They also serve to guide the roll 30 along the 5 slideway 21, 41, 42 and 61, as it is moved telescopically. As clearly shown herein projecting through cored holes in the blocks 42 are the jacks 360 on both the front and back sides of the machine. In line with the rails 10 370, as shown in Fig. 3 and Fig. 10, 10^a and 10^b, are shown the rails 376 supported on stands 378, which serve as a continuation of the tracks formed by the rails 370. It is, of course, evident that many means can be 15 provided for securing these rails to the supports, and preventing the trucks from running off the ends of the tracks, such as recesses in the stands, and plates at the ends of the rails respectively. It is an important 20 feature of my invention, that the stands 378 are higher than the stands 377, so that the outer ends of the rails 376 are elevated so as to incline inwardly towards the machine. Therefore, as the machine rolls out from its 25 normal position on to the rails 376, it will have an incline up which it must roll. This rise checks the tendency of the machine to roll off the ends of the rails 376.

After the removal of those parts which it 30 is necessary to take off the machine before it is in condition to move transversely, the next step is to place at the couch end of the machine on the jack 360 the rail 370. At the center of the machine the rail 370 is 35 placed on the stand 377 with its attached block 373 downward against the top of the support 377. A similarly constructed rail 370 is placed on the stand 377 at the breast end of the machine. The next step is to raise 40 the breast ends of the foundation rail 60 by means of the small jacks 196 on the side of the breast housing 195. This is clearly shown in Figs. 1^b and 8^b. The purpose of this small jack is to take the 45 weight off the pin 206 and the link 205 so that the nut 208 may be loosened after the removal of the dowel pin 209. Then the pin 206 may be withdrawn, freeing the link 205. The next step then is to apply power to gear 50 174 which is shown in Fig. 15, which causes the whole breast and housing with the fore-bay and head box supported thereon to be swung back away from the machine about the shaft 178 to a position shown in Fig. 8^b. Before this is done, however, the small jack 196 is lowered until the truck assembly 390' 55 rests on the rail 370. At the couch end of the machine the jack 360 is raised until the rail 370 mounted thereon receives the weight 60 of the couch end of the machine through the truck assembly 390'. By means of the jack 360 and the small blocks 373 on the rails 370 which do not have a counterpart on the other end of the rails, the rails are inclined 65 from the front of the machine, as shown in

Figs. 8, 8^a and 8^b, toward the back of the machine in Fig. 3. To illustrate this idea more clearly, the rail 370 as shown here at the couch end of the machine is similar to the rail 370 at the center of the machine and 70 the one at the breast end of the machine is higher at its right hand end than it would be at the left hand end. The adjoining end of rail 370, as has been described before, is lower than its left hand end shown here so that 75 the rails 370 and 376 are inclined toward each other. Thus as the parts within the wire loop are moved out transversely of the machine, they travel down the incline formed by rails 370 and are checked in their tendency to increase their speed by reason of the fact that they must travel up the incline formed by the rails 376. By properly proportioning the difference in elevation between the ends of the rails, it will be seen 80 that the movement of this heavy structure may be readily controlled without the use of any force other than gravity. After the parts have been moved out, as just described, the breast end housing is swung back into its 85 normal position by means of the gear 174 driven from a power source (not shown) about the pivot 178. The machine is now in position to receive the cable system which I have devised for stringing a new Fourdriner 90 wire in the form of a closed loop.

In Fig. 15, which is an end elevational view of the breast end housing, sections 199 of the breast housing have cored passages 200 extending therethrough, through the 100 walls of which the breast lock pins 201 pass, which are secured in place by means of the dowel pin 204 and the lock nut 202. The link 205 which extends into the cored passage has its side cut away to form concave surfaces 105 into which fit the ball plates 203. By this structure I attain, in effect, a universal joint between the breast housing and the side foundation rails.

In Figs. 16 and 17 are shown views of the 110 wire truck used in supporting a new wire in preparation for placing it on the machine.

All wires are shipped by the makers in long flat boxes, wound on poles, one pole 406 being within the wire loop on its outside end, 115 so as to prevent it being crushed or creased. The other two poles are wound around with the wire, and form a spool, one pole 419 being within the loop and the other, 419^a, on the outside, with only one thickness of wire 120 between them. In putting on the wire in the usual way, the extra pole 406 is removed as soon as the spool is taken from the box. In my invention, however, the pole 406 is left in the wire loop for future use.

In Fig. 17, which is a side view of the truck, are shown rings 402 and 402^a, that support a cable 401 by attachment to any suitable supports. Two trolleys, 403 and 403^a, with hooks, ride on the cable 401. 130

Swung from a suitable overhead support, are two large hooks 405 and 405^a.

After the wire loop containing the wire "W" is removed from its shipping case, it is placed on the wire truck within the platform 410, supported on the wheels 409. Secured at the ends of the platform 412 are frames 411, spaced apart sufficiently to permit a wire to pass between them. Members 411 also have stands 413 secured thereto, having bearings 414 which support a journaled counter bored plate 417, into which fit the two poles 419 and 419^a, and together form a revolvable spool for unwinding the wire W. After the spool formed by the poles 419 and 419^a is placed in the plates 417, it is held there by safety collars 415, on journals 416. The truck is now moved to the point where the cable 401 is stretched, and the pole 406 is lifted and hung on the hooks 405. The cable 401 is then threaded within the wire loop, as shown in Fig. 17.

As shown in Figs. 12 and 16, a series of spread pipes are provided on the wire truck 410, for a purpose which will appear shortly. A hollow pipe 420 is connected to a twin pipe 420^a, by means of a cable 421, provided with an eye bolt 422, while lower down on cable 421 is a hook 423, which is to be engaged within the eye bolt, so that the cable 421 is drawn up, causing 420^a to be supported near the pipe 420. At 425 are three pipes of the same length and similar to pipe 420. At 430, is a pipe similar to the pipe 420, and suspended under it is twin pipe 430^a, supported by the cable 431, eye bolt 432 and hook 433. Each of these pipe members is in turn fastened to the hooks 403, and slid within the wire loop, to the position shown in Fig. 12. The pole 406 is then removed from the hanger hooks and withdrawn from the wire loop.

Referring to the particular apparatus used to string the new wire in place, which is shown in Figs. 10, 10^a, 10^b, 12 and 12^a, of the drawings, 440 shows the first press stand adjacent the couch end of the machine which has not been shown in the other figures, and which forms no real part of this invention but is of the well known type, which supports a short strap 441 on an elevation with pin 10 of the top couch housing 11, while at the breast end of the machine are loops 444 mounted on the shaft 226 at the same level. Extending between these loops 444 and the strap 441 are two cables 446 secured to the strap by means of hook 445, one on the front and one on the back side of the machine. The apparatus 410 mounted on the wire truck which has been described is brought to the front side of the machine in line with the position previously held at the bottom couch roll 30 and is lifted off the truck and slid across the machine, will have one end resting on frame 21, the front side

of the machine, and on frame 21, on the back side of the machine. The cables 446 are now threaded through slots in the ends of the members 420, 425, 430, hooks 424 and 445, after which the cable is hooked into place 70 on the loops 444 and the straps 441. The cables 446 are then drawn taut by swinging the breast end housing back on its pivots, as shown in Fig. 12^a. As the cable is drawn taut by this motion, the members 420, 425 75 and 430 are drawn from the dotted position in Fig. 12 to the full line position marked W1. By this arrangement, the spread pipes and hooks 420, 424, 425 and 430 are strung like beads upon the cable 446. 80

I now take the pipe 420 and its twin 420^a and slide them along the cable 446 towards the breast roll end and follow them with members 424, 425 and 430. Meanwhile, the wire spool on its support unwinds, feeding 85 out the new wire W. At a predetermined point on the cables 446 an elongated button 450 is secured in such a manner that it may pass through the slots in the ends of the members 420, 424, 425 and 430, one in one 90 position, but when turned at right angles cannot pass through the slots. This button 450 turned in the position shown, acts as a lock and prevents the member 430 from sliding past it on the cable 446. At the position W2 is another elongated button 451 which locks the member 420 from sliding back towards couch end while members 424 and 425 are between the buttons 450 and 451. Meanwhile the wire is unwinding to 100 the position shown in W2. Members 430, 430^a and 424 are now dropped from the assembly moving toward the breast end and the other members 420, 424 and 425 are passed over the button 451 and are continued 105 along the cables 446 to the position marked W3, where one of the members 425 is dropped out of the system and held in place on the cable 446 by means of another button. Provision is made, as shown at 424, 110 424^a, by cable means to pass the transverse rails 370 through the wire loop to form a return track when the machine is moved transversely into its normal position. Before, however, any of the rails are put into 115 position within the loop, I prefer to fully extend the wire W. The elongated button 452 again locks member 420 from returning back over the cables. Members 424 and 425 are dropped from the train at this point to 120 be used in placing the transverse track 370 into place. As the member 420 continues in its movement along the cables 446, members 425 are dropped to convenient points along the cable until the members 420 and 420^a reach elongated button 453 adjacent the breast housing. At this point the hooks 423 engaged in eyebolts 422 are released, and the member 420^a is lowered until the cables 421 are stretched, causing the wire to now take the 125

form shown at W4. Likewise, at the couch end the wire is now extended and pole 419^a on the outside of the wire loop is removed as well as pole 419 on the inside of the wire loop. Member 430 locked at elongated button 450 forms the couch end of the loop and member 430^a is lowered by detaching hook 433 from eye bolt 432, permitting cable 431 to extend into the position shown by the 10 dotted lines just adjacent the couch housing 11. Cables 424 with extensions 420^a engage the ends of the beams 370 and support said beams as they are passed through the wire loop, as shown. At the breast and middle 15 sections beams 370 are now turned over, causing them to be inclined towards the front of the machine. At the couch end the jacks 360 are likewise lowered. The wire now being finally spread, as shown at W4, 20 Fig. 12, the forming cable couch roll and all the elements within the wire loop are now returned transversely to its normal position.

At this point, the wire is as shown in 25 Fig. 12, at W4, while the forming table has been shoved through the loop and rests on the rail 370. Jacks 360 are lowered, causing the couch end to again rest on the blocks 42, and pins 46 are forced up to lock 30 the saddle bearing 50 in place. The beam 370, at the couch end, is now free of weight, and is drawn out of the loop. The couch roll 30 is moved back along the slideway 61, 42, 41, 21, so as to take up the slack end in 35 the wire loop. At the breast end, 420^a is lifted up on the table roll 94, and 420 is slid back along cable 446 towards the couch end. The breast housing assembly is now swung back by means of gear 174, causing cables 40 446 to become slack and drop the members 424, 425, down on the table rolls 94.

Extension link 205, and lock pin 206 are secured in place, the breast elevation screw 180 raised, taking the weight of the machine 45 off the rails 370 at the breast and middle sections. These rails 370 are now removed by a cable trolley (not shown), extending beneath the rails 60. The cable trolley is then taken out of the way, rolls 84 are returned to their bearings, cables 446, members 420, 420^a, 424, 425, 430 and 430^a, are taken out of the way, couch roll 30 is returned to its normal position and secured in place, driving couch 32 is engaged, front 50 deckle 400 is put in place, deckle pole 105 is placed in rail-socket 101, deckle trough 160 is supported in sockets 157, and the back deckle is mounted in place. Top couch roll 1 is now swung down so that it rests on the bottom couch roll 30. The water connections are made at 71 and 75, the suction 55 pump and manifold are connected together at 132 and 133. The shake beam for the short breast stroke is now connected at 350, 60 which structure is not shown. The machine

is now turned back to its normal position with a new wire in place, and ready to run.

In Fig. 6 are shown details of the breast roll wipe board, comprising the yokes 300, having one end supported at the breast roll 70 journal 281 and the other end slidably secured to the rails 60, by means of slot 302, through which passes a bolt 301. A small bracket 303 is bolted on each arm 300, and has threaded into it an adjusting bolt 304, 75 which rests against the back end of the tapered bar 305, which supports the wipe board 306. By means of this arrangement, the position of the wipe board 306, with respect to the breast roll, may be varied. 80 On the outer ends of the arms 300, near the journals 281, are small bosses 307, cast solid with the arms 300. Secured to the ends of the journals 281 by bolts 309 are enlarged collars 308, having a cam 85 surface cut on their inner faces, which cooperates with the bosses 307. By means of this arrangement, as the journals 281 rotate, the arms 300 are given a transverse movement, so that the wipe board 306 oscillates back and forth across the face of the roll 380, so that it will not wear ridges on the roll. It will be noted that the cam faces are set in opposition to each other.

Referring now to Figs. 13, 14 and 15, at 90 Fig. 13 is shown an end view of the breast end, as it appears when withdrawn from the machine, disclosing its construction. Breast rolls 280 have grooved bearings, not shown, since this is the usual construction, and are mounted in bearings 290, having drop flanges 292, forming a loose slideway on rails 60. This gives additional clearance, as the structure 290 also has a shake motion independent of rails 60. The drop flange section 292 cross-braces the breast roll section of rail 60.

Drop flange 292 extends down along the side of the rail 60 as shown, forming a clearance space with the vertical section of rail 60 and a center pin 293 is secured to 95 292 and supports a bumper spring 294, between the drop flange 292 and rail 60 on the outside. These springs 294 are provided to ease the shake stroke.

It will be noted that the shake stroke is delivered to the box bearing 290, and being subject to wear it may change its stroke—but box 290 is securely bolted at 291 to rails 141, which in turn are cross-braced by beam 144 of the table section, which rests lightly on rails 60. Therefore, the breast roll is cradled by the boxes 290, rails 141, and cross beam 144, which transmit the short, 100 compound shake stroke to both the front 105 and back side structures.

In the present invention, the head-box, forebay and deckles shake with the long slow shake of the breast housing and side 110 foundation rail 60 and are independent of 115

the forming table, short, fast shake stroke. In Fig. 15, a short brace 173, on which is keyed gear 174 secures the front side of the machine to the back side, by means of 5 the journal bosses 178, cast solid with the framework through which screws 180 pass. The member 179 supports the brackets 182 in which are mounted the cross shaft 183, and worm 185, which meshes with worm 10 gear 186, threaded on the inside to receive the screw 180. The shaft 183 extends across the machine to a similar construction (not shown), in this figure. Suitable power means may be secured to the shaft 183 for 15 the purpose of changing the forming table elevation by the structure just described. The sections 195 are supported on the bell caps 181 and connected by a cross-brace 194. The cross-brace 198 connects sections 199 20 with a spring shake member arrangement 194*, secured to 194 as shown.

At 200 is shown a cored passage through the walls of which pass the lock pin 201 which secures the link 205 and the ball 25 plates 203 in place to form a flexible connection at this point.

Fig. 14 is a top plan view of Fig. 15 showing the elements which have been previously described from time to time.

30 In modern paper making machines it has been usual to construct the top couch roll with a heavy wool jacket, so that it would act as a brace for removing the water in the paper as it went between the couch rolls, 35 or, on the other hand, the lower couch roll is made hollow and its sides perforated to form the suction type of couch roll to remove the water by means of suction. As shown in Fig. 11, it is one of the purposes 40 of my invention to so construct the couch housing and bearings that either type of roll may be easily used by my improved machine. In place of the smooth lower couch roll 30, I propose to substitute as an alternative the hollow perforated couch roll 500 45 equipped with clutch 501, having on one of its bearing supports a packing box 502, connection 503, joined by a short section (not shown) at 505 which in turn is connected 50 to a cycloidal suction pump or any other suitable suction means. Suction couch roll 500 is disconnected as usual, at the packing box 502, permitting roll 500 to slide back on to rails 61 between top-couch side housings 11. The suction couch roll 500 is 55 shown telescoped back and resting on rail 61 and transverse tracks 370 and 376 placed on an incline so that the roll structure may be easily shifted as an integral unit with 60 the forming table.

In this construction, as in the construction using a couch roll of the type shown at 30 in Fig. 1, the oversize bearings 31 may be used with the suction couch of the type 65 shown in this figure. These bearings are

hollow and provide a suction passage from the drum through 502, 503 and 508.

As far as I am aware, no attempt has been previously made to so construct the couch end of the machine as to make it capable of using either the ordinary press couch rolls or the suction couch roll which is usually used in making papers with a duplex surface.

By the constructions which I have shown, 75 a couch and jacket roll 30 and 1, respectively, can be used on colored papers of light weight, while on the half-tone superplate or stock to be converted into coated papers, the suction roll of the type indicated by the 80 reference numeral 500 can be used by merely substituting a smooth roll for the suction roll.

This change from the roll of one type to the roll of another type may be easily effected without removing the transversely movable part of the machine from within the wire loop but the wire may be slackened by moving the lower roll forward on to the offset section of rails 60, and then replaced 90 by the desired roll.

By this simple construction I have effected an interchangeable couch roll system. Therefore, by merely changing the system of couching, the paper machine can be 95 made to conform to the best principles and practices of paper making.

I am well aware that many changes in detail of construction may be made by one skilled in the art, without resorting to invention, and I do not, therefore, desire to be limited except as pointed out in the appended claims.

What I wish to secure by United States Letters Patent is:

1. In a paper making machine, a transverse movable forming table and gravity means for causing the transverse movement.
2. In a paper making machine having a sealed couch side housing, a transversely movable forming table and gravity means for moving said table transversely of the main structure.
3. In a paper making machine, a sealed couch side housing, a transversely movable forming table constructed so that the bottom couch roll moves transversely with said forming table, and means for causing said transverse movement.
4. In a paper making machine, a sealed couch side housing, a transversely movable forming table, and means for moving said table.
5. In a paper making machine, the combination of a transversely moving forming table, and means for causing the transverse movement, comprising trucks and inclined rails.
6. In a paper making machine, a main frame comprising foundation rails, a mov-

- able breast housing structure, and means for transversely moving all the parts within the wire loop.
7. In a paper making machine, the combination of an oscillatable breast end housing, a transversely movable forming table, and means employing the force of gravity for effecting the transverse movement.
8. In a paper making machine, the combination with a transversely movable forming table of a longitudinally movable couch roll.
9. In a paper making machine, the combination of a movable breast end structure, including forebay slices and headbox with a transversely movable forming table, and gravity means for causing the transverse movement.
10. In a paper making machine, the combination of a transversely movable forming table, means for moving the bottom couch roll longitudinally, means on the couch side housing for swinging the upper couch roll out of operative position and means for effecting the transverse movement.
11. In a paper making machine, the combination of a transversely movable forming table, including the bottom couch roll and breast roll, a rail system extending transversely of the machine and forming with truck structures means for effecting transverse movement of the table, and a sealed couch side housing.
12. In a paper making machine, the combination of a sealed couch side housing, a longitudinally movable lower couch roll and a jaw clutch mounted on said couch roll and movable with it.
13. In a paper making machine, the combination of a transversely movable forming table, a sealed couch housing and gravity means whereby either a plain or suction couch roll may be used.
14. In a paper making machine, the combination of a transversely movable forming table, a sealed couch side housing and a longitudinally movable lower couch roll having a jaw clutch secured thereto whereby said couch roll and clutch may be moved as a unit longitudinally to a seat on the forming table for transverse movement with it.
15. In a paper making machine, the combination of a transversely movable forming table and a sealed couch side housing.
16. In a paper making machine, the combination of a transversely movable forming table, a sealed couch side housing and a longitudinally movable couch roll, said side housing being so constructed that said longitudinal movement may be effected without removing said sealed side couch housings.
17. In a paper making machine, the combination of a transversely movable forming table, means for swinging the upper couch rolls out of operative position, a sealed side couch housing, and a longitudinally movable lower couch roll said housings and lower couch roll being so constructed that either a pressure or a suction couch roll may be used without disturbing the sealed couch 70 housing.
18. In a paper making machine, the combination of a transversely movable forming table, comprising all of the parts within the wire loop, and means for effecting the transverse movement, including a plurality of inclined rolls and cooperating trucks.
19. In a paper making machine, the combination of a transversely movable forming table, comprising all the parts within the 80 wire loop, and means for effecting the transverse movement comprising rails and trucks, said rails being adapted to be elevated at one end.
20. In a paper making machine, the combination of a transversely movable forming table, and means for effecting the transverse movement, comprising a plurality of rails made in two sections, with their outer ends higher than their inner adjoining ends. 90
21. In a paper making machine, the combination of a transversely movable forming table, means for effecting the transverse movement comprising a plurality of rails made in two sections, with the outer side 95 higher than the inner adjoining ends, and means for changing the elevation of the rails, whereby the movable section may be returned downhill to its normal position.
22. Means for effecting transverse movement of the forming table of a paper making machine, comprising a plurality of two section rails, some of which are mounted on elevating screws, others on stands of different elevations, and others having blocks 100 on one end only whereby the outer ends may be made higher or lower than the inner ends, and trucks mounted on the forming table, and adapted to run on said rails.
23. In a paper making machine, the combination of a transversely movable forming table, means for effecting the transverse movement, comprising a plurality of rails made in two sections, with their outer ends higher than their inner adjoining ends, and 115 means for aligning the forming table when returned to normal position.
24. In a paper making machine, the combination of a movable forming table, a self-contained breast end housing, forebay and 120 headbox adapted to swing out of operative position as a unit, and means for tying said breast housing to the main frame of said forming table.
25. In a paper making machine, the combination of a transversely movable forming table, a breast end unit means for effecting the transverse movement, comprising a plurality of rails made in two sections, with their outer ends higher than their inner ad- 130

- joining ends, and a flexible connection between said breast unit and said forming table.
26. In a paper making machine, the combination of a transversely movable forming table, a breast end unit means for effecting the transverse movement, comprising a plurality of rails made in two sections, with their outer ends higher than their inner adjoining ends, and a detachable connection between said breast unit and said forming table.
27. In a paper making machine, the combination of an oscillatable breast housing, a transversely movable forming table and a stationary couch housing.
28. In a paper making machine, the combination of an oscillatable breast housing, a transversely movable forming table, said forming table having its side rails of different lengths.
29. In a paper making machine, the combination of an oscillatable breast housing, a transversely movable forming table, and a stationary couch housing, said couch side housing having movable supports for the upper couch roll.
30. In a paper making machine, the combination of a breast housing unit comprising a headbox box, deckel frame and forebay, a transversely movable forming table, including the breast roll, sealed couch side housing constructed to permit the lower couch roll to slide therethrough on to the end of the forming table for transverse movement with it, and means for effecting the transverse movement.
31. In a paper making machine, the combination of a transversely movable forming table, a sealed couch housing and means on said forming table and couch housing for aligning the forming table in place on its return to normal position.
32. In a paper making machine, the combination of a breast housing adjustable in elevation, a transversely movable forming table having table roll suction boxes mounted thereon, comprising a wide flanged edged vacuum box and suction head seals secured thereon, and a sealed couch housing.
33. In a paper making machine, the combination of a transversely movable forming table including a forming wire and table roll suction boxes comprising flanged suction boxes having table rolls therein, suction head seals secured to said flanged boxes and means on heads for sealing the ends of the wire.
34. In a paper making machine, the combination of a transversely movable forming table, a breast roll, table roll suction boxes, deckle supports on said roll boxes, said supports being mounted on said table for transverse movement with it, and means for moving said forming table transversely on an incline.
35. In a paper making machine, the combination of a transversely movable forming table, table suction roll boxes and a suction manifold mounted on said table, and means for moving said table transversely.
36. In a paper making machine, the combination of a transversely movable forming table, a water distributing system, suction boxes and deckle supports mounted on said table, and means for effecting transverse movement, comprising a system of inclined rails.
37. In a paper making machine, the combination of a transversely movable forming table, a breast wipe board mounted on said table, and means for giving it a reciprocating transverse movement.
38. In a paper making machine, the combination of a transversely movable forming table, a breast wipe board mounted on said table, and cam means for giving it a reciprocating transverse movement.
39. In a paper making machine, the combination of a stationary sealed couch housing, a transversely movable forming table, and a self-contained breast housing so connected to the table that it may be moved with a compound short and long breast stroke.
40. Means for stringing a Fourdrinier wire in the form of a closed loop comprising a cable system extending the length of the machine, means on said cable system for supporting the wire, and means for spacing the supporting members at intervals on said cable system.
41. In a paper making machine, the combination of an oscillatable breast housing, means for causing such movement, a transversely movable forming table and means for moving the table into and out of operative position whereby all the parts within the wire loop may be removed.
42. Means for stringing a Fourdrinier paper making machine comprising means for moving all the parts within the wire loop transversely thereof, means for supporting a new wire in the form of a loop, and means for returning said movable means back within the loop.
- In testimony whereof I have hereunto set my hand on this 23rd day of January A. D., 1926.

JAMES K. DARBY.
